ROTATABLE ADSORPTION APPARATUS

Ernest B. Miller, Houston, Tex., assignor to Jefferson Lake Sulphur Company, New Orleans, La., a corporation of New Jersey

Application January 24, 1949, Serial No. 72,426

5 Claims. (Cl. 183—4.6)

1

This invention relates to fluid treating apparatus of the type in which fluids, either liquid or gaseous, are brought into contact with the treating material, either a reactant material to effect a chemical reaction, and/or an adsorbent material to absorb liquid or gaseous products from the fluid being treated, and in which the treating material is stripped of its adsorbed products and/or is regenerated for further use. The present invention has more particular reference to fluid treating apparatus of the so-called rotary or continuous type.

One object of the present invention is to provide a rotary type fluid treating apparatus in which a plurality of foraminous, annular containers, filled with the treating material, are continuously and successively moved into and through one or more treating sectors or zones, and then into and through an activating or regenerating sector or zone in which the treating material is prepared for a repetition of the cycle.

Another object of the invention is to provide fluid treating apparatus, as characterized above, in which a large surface area of relatively thin beds of fluid treating material offering a minimum of resistance to the flow of the fluids is condensed into a small cubic space.

Another object of the invention is to provide fluid treating apparatus, as above characterized, in which baffle members are provided to insure an even flow of the fluids through the treating material, thereby making effective use of all of the treating material and increasing the efficiency and capacity of the apparatus.

Another object of the invention is to provide fluid treating apparatus, as above characterized, in which the temperature of the fluid undergoing treatment may be controlled in the various treating sectors or zones, or stages, by means of heat exchangers connected in series with and between each of such sections or zones.

A further object of the invention is to provide fluid treating apparatus, as characterized above, in which the annular containers may readily be removed and replaced.

A still further object of the invention is to provide an improved apparatus for conditioning air.

Other objects and advantages of the invention will appear in the specification when considered in connection with the accompanying drawings, in which:

Fig. 1 is a side elevational view of the fluid treating apparatus of the invention;

Fig. 2 is a top plan view of the apparatus shown in Fig. 1;

2

Fig. 3 is a vertical sectional view taken on the line 3—3 of Fig. 2;

Fig. 4 is a horizontal sectional view of the rotatable annular drum taken on the line 4—4 of Fig. 1;

Fig. 5 is an enlarged vertical sectional view of the seal shown in the upper manifold in Fig. 3;

Fig. 6 is a vertical sectional view taken on the line 6—6 of Fig. 5;

Fig. 7 is a top plan view of an annular fluid treating material container;

Fig. 8 is a vertical sectional view, with parts broken away, taken on the line 8—8 of Fig. 7;

Fig. 9 is a schematic view to show the course of the fluid being treated through the first and second stages of the apparatus, and the flow of regenerating fluid through the activation stage; and

Fig. 10 is a schematic sketch showing the relation of the fluid velocities and pressures on the upstream and downstream side of a barrier in a duct.

Prior rotary fluid treating apparatus were usually of two types. One type, as shown for example in the patent to Karlsson et al., No. 2,347,829, and the patent to Campbell, No. 2,304,398, provides compartments filled with a fluid treating material. The fluid treating material in each compartment is in one compact mass and offers high resistance to the flow of the fluids therethrough and, too, due to its compactness entraps such a quantity of the fluid being treated as to require a purging of the material before it is regenerated. The other type, as shown for example in my copending application Ser. No. 655,213, now Patent 2,507,607 issued May 16, 1950, for Method of and Apparatus for Conditioning Air, provides elongated, foraminous containers in each of the compartments for holding thin layers of the treating material. While this construction provides less resistance to the flow of the fluid therethrough and insignificant entrapment of the fluid therein, it still does not insure the uniform flow of the fluid through the fluid treating material in the foraminous containers, which results in a loss in the effective use of the material and a reduction in the capacity of the apparatus.

In general, the present invention comprises an open-ended axially compartmentized, annular rotary drum having at least one foraminous annular container filled with a fluid treating material located in each compartment; baffle members associated with each container to insure uniform flow of the fluid through all of the material in the container; a pair of vertically spaced, sta-

50
40

20
15
10

tionary annular manifolds divided into a plurality of separate sectors by radial seals or partitions, with each sector having a fluid conduit connected thereto and having an opening therein for the passage of fluid; and means for rotating the annular drum, whereby the openings in the compartments in the drum are successively brought into communication with the openings in the corresponding sectors of the manifolds to permit the successive axial flow of fluids through the compartments of the drum.

While the apparatus of the present invention may be employed for treating fluids, either liquid or gaseous, for various purposes, it will be described, by way of illustration, as used to condition air.

In general, the rotatable compartmentized drum, the manifolds and the seals therein, and the heat exchangers are similar to that shown in my aforesaid co-pending application. However, the construction and arrangement of the foraminous containers for the fluid treating material and the baffles associated therewith are novel.

Referring now to Figs. 1, 2 and 3, there is shown a rotatable annular drum 10 mounted within a suitable structural frame, shown as having four legs 11 bent over the top of the drum, each being connected to a plate carrying an upper vertical guide bearing 12 for a central vertical shaft 13 having a lower step bearing 14 mounted on cross beams 15 secured to the legs 11 of the supporting frame near the bottom thereof. Upper and lower radial arms or spokes 16 connect the shaft to the drum. Rotation of the drum is effected by means of a gear 17 fixed to the shaft 13 and meshing with a gear 18, driven by any prime mover, such as a motor 19, mounted on one of the cross beams 15 near the bottom of the frame.

The rotatable annular drum is shown as being divided into a plurality of compartments 20 by radial partitions or diaphragms 21. The top of the drum is provided with an annular opening 22 which is closed by a stationary top manifold 23 fixedly attached to the frame. The bottom of the drum is also provided with an annular opening 24 which is closed by a stationary bottom manifold 25 fixedly attached to the cross beams 15.

To prevent the escape of air between the rotating drum and the top and bottom manifolds, sealing ring gaskets 26 are placed at the junction of the manifolds and the drum. The sealing gaskets 26 are carried by angles 27, against which a plurality of circumferentially spaced spring plungers 28, mounted on brackets 29 attached to the manifolds, act to hold the gaskets in tight sealing engagement.

In each of the radial compartments 20, near the bottom thereof, there is provided a plate 30 attached to the walls of the compartment, as by welding, to form a gas-tight joint. The plate 30 forms a support for one or more elongated, annular adsorbent containers 31. The adsorbent containers 31 are identical in construction and, as best shown in Figs. 7 and 8, each comprises two concentric tubular screens 32, 33 held in spaced apart relation by a plurality of longitudinal radial fins 34, with the annular space between the screens closed at the bottom, as by a flanged annular plate 35. The mesh of the screens is such as to retain a granular fluid treating material 36 in the annular space between the screens. In the instant case, the fluid treating material 36 may be any adsorbent having characteristics substantially like silica gel or the gel of other acti-

vated hydrous oxides. Preferably, silica gel is used.

Each of the containers 31 is closed at its top by means of concentric hoops or metal bands 37, 38 mounted on the concentric screens 32, 33, and a cover plate 39 detachably connected to the inner hoop or band 38, as by screws, and having a depending annular flange 40 fitting between the hoops or bands 37, 38. A depending cylindrical fin 41 is secured to the flange 40 and projects downwardly between and below the hoops or bands 37, 38, and fits in slots 42 formed in the upper ends of the radial fins 34, all as shown in Figs. 7 and 8. The construction is such that, as the silica gel settles down, leaving a space between the top portion of the wire screens devoid of silica gel, the fin 41 will prevent air from passing through that space.

Mounted within the inner wire screen 33 is an inverted substantially conically shaped baffle member 43, as best seen in Fig. 8. The baffle member is closed at its apex which extends downwardly to a point near the bottom of the container and has its upper peripheral edge suitably secured to the band 38, as by welding. Preferably, the baffle member 43 is made of thin sheet metal.

Each container has its bottom end detachably mounted in a socket formed on plate 30, as by means of a ring collar 44, welded thereon. The bottoms of the sockets have openings 45 formed therein which correspond in size and are aligned with the open bottom ends of the annular adsorbent contains, as clearly shown in Fig. 3.

In each of the radial compartments 20, near the top thereof, there is provided a plate 46 attached to the walls of the compartment, as by welding, to form a gas-tight joint.

Mounted in each of the compartments 20 and extending between the bottom plate 30 and the upper plate 46 therein, is a substantially frustoconically shaped baffle member 47, one for each of the annular containers mounted in the compartment. The baffle member 47 encompasses the annular container 31 and has its upper peripheral edge secured to the edge of a circular opening 48 formed in the upper plate 46, as by welding, and has its lower peripheral edge secured to the upper peripheral edge of the ring collar 44 on the lower plate 30, as by welding. It should be noted that the annular space between the outer frusto-conical baffle 47 and the inner conical baffle 43 forms an open ended conduit or duct and that the annular bed of adsorbent material forms a barrier extending longitudinally across the duct, all as shown in Fig. 3. The particular function of the baffle members 43 and 47 will be hereinafter pointed out.

At three spaced circumferential points in the top and bottom manifolds there are located seals 49 arranged in vertically aligned pairs which, by reason of the sliding contact of the radial partitions 21 against the under face of the bottom of the seals, divides the manifolds and drum into three sectors or zones, each sector being gas-tight with respect to the adjacent sectors. The seals are identical in construction and the details thereof are best shown in Figs. 5 and 6.

Each seal is shown as being mounted between partition walls 50 extending across the manifold. The top or cover plate 51 of the seal is detachably secured to the manifold, as by bolts. The bottom of the seal rests on the top or bottom of the drum, as the case may be, and includes a sealing plate 52 having upturned

5

flanges on its ends adapted to fit against the partition walls 50 and having its under surface, including the flanges, covered with a layer of sheet asbestos or rubber material 53 to engage the ends of the radial partitions. The arrangement is such that the seals can be easily removed so that the asbestos liners can be inspected and replaced. In addition, the top seals provide openings through which the annular adsorbent containers 31 can readily be removed for renewal or repair. The bottom or sealing plate 52 of the seal is adjustably held in position against the drum, as by means of stems 54 fixed thereto and extending upwardly through U-shaped brackets 55 bolted to the side walls of the manifold. Coil springs 56, mounted on the stems between the arms of the bracket, press against discs 57 fixedly attached to the stems to urge the stems and bottom plate downward.

Each radial partition or diaphragm 21 has that portion of its top and bottom edges extending between the edges of the openings in the top and bottom of the drum, covered by a strip 58 of reinforced asbestos cloth or other suitable sealing material folded thereon and detachably secured thereto, as by bolted clamping strips 59. This asbestos strip engages the under side of the seal, as best shown in Fig. 6.

The width of the seal with respect to the compartments 20 containing the adsorbent units is such that at all times at least one of the partitions or diaphragms 21 is engaging the sealing plate of the seal in air-tight engagement. As is clearly seen from the foregoing, the air dehydrating unit is divided into three gas-tight sectors or zones by the engagement of the radial partitions or diaphragms with the seals.

As the drum carrying the annular adsorbent containers rotates, they are continuously and successively moved through the three sectors or zones, called, for convenience, the first stage, the second stage, and the activation stage. The flow of the air through the first and second dehydration stages and the flow of the hot gases through the activation stage is schematically shown in Fig. 9. The outside air from which moisture is to be removed is supplied to the air dehydrating unit at a sufficient pressure to force it through the system and enters the top manifold of the first stage by means of the conduit 60. Then it flows from the manifold through the opening in the top of the drum into the various compartments of the drum containing those adsorber beds which are at that time contained within the sector forming the first stage. The air passes downwardly into the frusto-conical baffle 47, through the pervious layers of adsorbent material, which removes part of the moisture content therefrom, into the interior of the annular adsorber beds; thence, downward through the openings in plate 30 into the bottom of the drum and through the opening therein into the bottom manifold. From the bottom manifold, the now partially dried air passes through conduit 61 into a heat exchanger or intermediate cooler 62, where it is cooled to about room temperature. The cooler 62 may be of the water-circulating type. From the intermediate cooler, the air moves, by means of conduit 63, which extends underneath the device and up one side to the top thereof, into that portion of the top manifold leading to the second stage. The air moves downwardly through the second stage, in a manner similar to its downward movement through the first stage, into the bottom manifold of the second

6

stage, the remainder of the moisture content of the air being removed during its passage through the second stage.

From the bottom manifold of the second stage, the now dried air moves through conduit 64 into a second heat exchanger or cooler 65, where it is cooled to the desired room use temperature. The cooler 65 may also be of the water-circulating type. From the second cooler 65, the now dehydrated and cooled air is conveyed through conduit 66, to the various points of use.

The removal of moisture from the adsorbent material carried by the adsorber units is effected in the activation stage. Atmospheric air is forced by a fan 67 through a heater 68, then through conduit 69 into the bottom manifold of the activation stage. From the bottom manifold the hot air passes through the opening in the drum into the bottom of such of the various compartments of the drum as are at that time contained within the sector forming the activation stage; thence upwardly through the openings in the plates 30 and up into the interior of the annular adsorber units, through the pervious solid layer of adsorbent material into the interior of the frusto-conical baffle 47, and then into the upper portion of the compartments of the drum. As the hot air passes through the adsorbent material it removes the moisture therefrom. The hot moisture-laden air then passes upwardly through the opening in the top of the drum into the top manifold and from the top manifold is exhausted into the atmosphere through conduit 70.

The operation of the device is as follows:

With the annular drum continuously and slowly revolving counterclockwise, as viewed from the top, the adsorbent container beds are successively moved through the first stage, then through the activation stage, and then through the second stage. The wet air to be dehydrated is first passed through the first stage, then through the intermediate cooler into and through the second stage, where the remaining moisture is removed by the freshly dried adsorbent material. From the second stage, the now dried air is passed through a second cooler and then conducted to the points of use. The use of a second cooler may be omitted, if desired, and the air discharged directly to the points of use.

The baffles 43 and 47 insure substantially uniform flow of fluid through the silica gel in the annular containers, whether the flow of fluid is downward, as in the case of the air being dehydrated, or upward as in the case of the heated activating medium.

The movement of a fluid from one part of a system to another depends upon differences of static pressure. The fluid will flow from a region of higher static pressure to one of lower static pressure. The pressure difference may be very slight for a low velocity movement, or it may be considerable for high velocity movement of fluid.

The total pressure of a body of moving fluid is made up of two components: static pressure and velocity pressure. The velocity component is the pressure equivalent of the energy required to keep the fluid in motion. Velocity pressures are very low in slow moving fluids but increase in proportion to the square of the velocity so that rapidly moving fluids have considerable velocity pressure.

The total pressure of a given body of moving fluid in a short duct will not be appreciably dif-

ferent for any part of the duct, but if the velocity changes at any point, due to a change in cross sectional area of the duct, the velocity component will change, causing a complementary change in the static pressure component.

Where the flow of a fluid is to be directed through a barrier of large area and low resistance at a slow velocity, only a slight difference in static pressure will be needed. Consequently, there will be only a small difference in the total pressure on either side of the barrier. If the fluid approaches and leaves the barrier at high velocities, the velocity component of the total pressure may be as much as or more than the static component. If this velocity pressure component varies considerably over the face of the barrier, the static pressure component which governs the flow through the barrier will also vary, resulting in unequal distribution of flow over the face of the barrier.

If a uniform flow distribution through the barrier is required, it is essential that no substantial differences in velocity pressure exist in the fluid along the face of the barrier either on the upstream or the downstream side.

As above pointed out, the elongated annular space between the inner and outer baffles 43, 47 forms an elongated duct which is annular in cross section. The elongated annular adsorbent container filled with silica gel is positioned in the duct between the baffle members in such manner that it forms a barrier extending diagonally across the duct from top to bottom.

The diameter of the bases and the tapers of the side walls of the baffle members 43, 47 are such that the cross sectional area of the duct formed between the two members is substantially equal at its top and bottom. The tapers of the side walls of the two baffle members are such that a substantially uniform velocity is obtained on both sides of the barrier as fluid is transferred from the upstream to the downstream side, regardless of the direction of flow, thereby creating a substantially constant static head over the face of the barrier, resulting in a substantially uniform distribution of the fluid through the entire barrier area.

This is diagrammatically illustrated in Fig. 10, where the downstream and upstream portions of the duct formed by the walls of the frusto-conical baffles 43 and 47 are shown with the tubular container filled with silica gel forming the barrier B.

P_1 is the total pressure on the upstream side of barrier.

P_2 is the total pressure on the downstream side of barrier.

S_1 and S_2 are the static pressure components at the inlet and outlet ends on the upstream side of the barrier.

V_1 and V_2 are the corresponding velocity pressure components.

S_3 , S_4 , V_3 and V_4 represent the analogous condition on the downstream side of the barrier.

$$P_1 = S_1 + V_1 = S_2 + V_2$$

$$P_2 = S_3 + V_3 = S_4 + V_4$$

The upstream and downstream ducts adjacent to the barrier are tapered so that a constant velocity is obtained on both sides of the barrier as fluid is transferred from the upstream to the downstream side. In effect, $V_1 = V_2$ and $V_3 = V_4$, so that S_1 and S_2 differ from P_1 in the same degree, and S_3 and S_4 differ from P_2 in the same degree. The static head is thus a constant value over the face of the barrier, resulting in a sub-

stantially uniform distribution of fluid through the entire barrier area.

Thus, it will be seen that by using the baffle members the entire barrier area is made full use of with resultant increases in efficiency, capacity and economy.

While the invention has been described as having the annular drum rotating counterclockwise, obviously, the device would be operable with the annular drum rotating clockwise, by changing the positions of the stages. Further, while only one activating stage is shown, obviously, a second activating stage could be used between the first and second dehydrating stages, and, further, the various stages could be multiplied and combined in various manners.

Obviously, the invention is not restricted to the particular embodiment thereof herein shown and described. Moreover, it is not indispensable that all of the features of the invention be used conjointly, since they may be employed advantageously in various combinations and sub-combinations.

What is claimed is:

- 25 1. In an apparatus for treating fluids, the combination comprising a frame; an annular drum having annular openings in its top and bottom rotatably mounted therein; a plurality of vertical partitions mounted in said drum dividing it into a plurality of radial compartments; a vertically spaced pair of transversely extending partitions mounted in each compartment and forming a gas-tight joint with the walls thereof; at least one open-ended frusto-conically shaped baffle member mounted in each of said compartments and extending between the upper and the lower transverse partitions and providing a fluid passage between the top and bottom of the compartment; an elongated annular foraminous fluid treating material container mounted in each baffle member, said container being closed at its top and having its hollow interior at its bottom end opening into the bottom of the conduit and having an inverted conically shaped baffle member mounted in its hollow interior with the base of the conically shaped baffle secured to the container adjacent its top end and the apex extending to a point adjacent its bottom end, the construction being such that the annular space between the baffle members forms an elongated frusto-conically shaped conduit annular in cross section with the container forming a barrier extending longitudinally across the conduit from the top to the bottom, and with the taper of the side walls of the conduit being such that the cross sectional area of the conduit on each side of the barrier varies so as to maintain a substantially constant velocity of the fluid on either side of the barrier throughout its extent regardless of the direction of flow of fluid in the conduit resulting in uniform flow through the entire barrier area; an upper annular manifold fixedly mounted on said frame and communicating with the opening in the top of the drum; a lower annular manifold fixedly mounted on the frame and communicating with the opening in the bottom of the drum; a plurality of seals located in each of said manifolds and cooperating with said partitions to divide the drum and the manifolds into a plurality of sectors, each sector being gas-tight with respect to its adjacent sector; and means for rotating the drum whereby said compartments with the containers are continuously and successively moved through each of

2. In an apparatus for conditioning air, the combination comprising a frame; an annular drum having annular openings in its top and bottom rotatably mounted therein; a plurality of vertical partitions mounted in said drum dividing it into a plurality of radial compartments; a vertically spaced pair of transversely extending partitions mounted in each compartment and forming a gas-tight joint with the walls thereof; at least one open-ended frusto-conically shaped baffle member mounted in each of said compartments and extending between the upper and the lower transverse partitions and providing a fluid passage between the top and bottom of the compartment; an elongated annular foraminous adsorbent container mounted in each baffle member, said container being closed at its top and having its hollow interior at its bottom end opening into the bottom of the conduit and having an inverted conically shaped baffle member mounted in its hollow interior with the base of the conically shaped baffle secured to the container adjacent its top end and with the apex extending to a point adjacent its bottom end, the construction being such that the annular space between the baffle members forms an elongated frusto-conically shaped conduit annular in cross section with the container forming a barrier extending longitudinally across the conduit from the top to the bottom, and with the taper of the side walls of the conduit being such that the cross sectional area of the conduit on each side of the barrier varies so as to maintain a substantially constant velocity of the fluid on either side of the barrier throughout its extent regardless of the direction of flow of fluid in the conduit resulting in uniform flow through the entire barrier area; an upper annular manifold fixedly mounted on said frame and communicating with the opening in the top of the drum; a lower annular manifold fixedly mounted on the frame and communicating with the opening in the bottom of the drum; a plurality of seals located in each of said manifolds and cooperating with said partitions to divide the drum and the manifolds into a plurality of sectors, each sector being gas-tight with respect to its adjacent sector; means for passing heated gases through one of said sectors; means for passing air to be dehumidified in succession through the other of said sectors; and means for rotating the drum whereby said compartments with the containers are continuously and successively moved through each of said sectors.

3. In fluid treating apparatus of the type wherein the fluid to be treated is caused to pass through at least one conduit having a spaced pair of openings therein and containing granular fluid treating material capable of effecting the desired treatment, the improvement which comprises a foraminous container for holding the granular fluid treating material, said container being mounted in said conduit between said openings and positioned to act as a barrier through which the fluid flowing through the conduit must pass, said barrier extending longitudinally and diagonally of the conduit from one side wall to the opposite side wall and dividing it into two oppositely tapered passageways with the cross sectional area of each passageway con-

stantly decreasing from its large end toward its small end and the areas at their larger ends being substantially equal so as to maintain a substantially constant velocity of the fluid on either side of the barrier throughout its extent, regardless of the direction of flow of the fluid, resulting in a substantially uniform flow throughout the entire barrier area.

4. An apparatus for treating fluid comprising a rotary member having a plurality of axially extending fluid conduits therein, each of said conduits having a spaced pair of openings formed therein; a foraminous container mounted in each of said conduits between said openings, each of said containers being adapted to hold a granular fluid treating material and being mounted in its respective conduit to act as a barrier through which fluid flowing through the conduit must pass, said barrier extending longitudinally and diagonally of the conduit from one side wall to the opposite side wall and dividing it into two oppositely tapered passageways with the cross sectional area of each passageway constantly decreasing from its large end toward its small end and the areas at their larger ends being substantially equal so as to maintain a substantially constant velocity of the fluid on either side of the barrier throughout its extent, regardless of the direction of flow of the fluid, resulting in a substantially uniform flow throughout the entire barrier area; and a pair of vertically spaced, stationary, annular manifolds having radial partitions therein dividing them into a plurality of separate corresponding sectors, each of said sectors having a fluid conduit communicating therewith and having an opening therein for the passage of fluid; said manifolds being mounted to slidably engage said rotary member as it rotates and being positioned so that the vertically spaced openings in said conduits will be brought successively into communication with the openings in the corresponding sectors of the vertically spaced manifolds respectively, as the rotary member rotates, whereby successive axial flows of fluid will take place through the conduits in the rotary member as said rotary member rotates.

5. Apparatus for treating fluid, as set forth in claim 4, wherein the conduits are frusto-conical and are annular in cross section; and wherein the foraminous containers are tubular and are annular in cross section.
